UNITED STATES PATENT OFFICE.

JOHN BERG, OF ANDERSON, INDIANA.

COMPUTING CHEESE-CUTTER.

No. 806,454.

Specification of Letters Patent.

Patented Dec. 5, 1905.

Application filed July 26, 1904. Serial No. 218,288.

To all whom it may concern:

Be it known that I, JOHN BERG, a citizen of the United States, residing at Anderson, in the county of Madison and State of Indiana, 5 have invented certain new and useful Improvements in Computing Cheese-Cutters, of which the following is a specification.

This invention relates to improvements in means for ascertaining the correct size of slice 10 of a value called for that should be cut from a circular cheese of a known value and to means for expeditiously and accurately cutting off the quantity indicated.

The cheese will be mounted on a rotary table 15 and will be brought by the rotation of the table under a knife moving in a vertical plane.

The object of this invention is to provide a simple, inexpensive, and durable machine; second, to provide a worm-gear movement for 20 positively rotating the table and holding it at a given position; third, to provide means for raising and lowering the cutting-knife, whereby its inner corner will move on a substantially straight line while passing through the 25 cheese, so as to avoid cutting past the center and crumbling the cheese there, as is inevitable with an ordinary swinging movement of the knife, and a fourth object is to provide a convenient and accurate price-indicator and 30 gage.

I accomplish the objects of the invention by the mechanism illustrated in the accompanying drawings, in which—

Figure 1 is a top plan view of my invention 35 with the knife-handle and knife and also the platform or table removed and showing some of the parts broken away; Fig. 2, a side elevation and partial vertical section of same; Fig. 3, a detail in plan view of the base or 40 inner end of the knife-handle. Fig. 4 is a side view, partially in section, and Fig. 5 a front view, of the price-indicator and gage; and Fig. 6 is an enlarged detail of the worm-shaft, showing in section the means of securing the 45 indicator-hands and stop mechanism thereto.

Like characters of reference indicate like parts throughout the several views of the drawings.

A represents the base of the machine and 50 comprises an annular horizontal platform supported on suitable legs and having radial arms, here shown as three in number, which meet and support a depressed center hub having the pin R, on which is mounted the revolvable metal plate B, having a center hub, to

the under side of which a worm-gear G is fastened, so as to move with the hub. A circular board C is fastened, by means of screws, to the plate B, and the cheese A A is deposited upon this board with its center above the center of the board. 60

D D represent a pair of brackets which are parallel with each other and are bolted to the base-plate. They have the horizontal slots P and the cam-slots O, which start on a level 65 with slots P and extend upwardly and rearwardly, then upwardly and forwardly, and then in a curve rearwardly.

E is the handle or lever to which the knife F is bolted. It has a bifurcated rear end, as 70 shown in Fig. 3, and L is a pin carried by the plural members of the handle. The ends of this pin pass into the slots P of the brackets. The plural members of the handle also have the pin N, on the ends of which are the rollers 75 M M, which enter the respective cam-slots O.

Taking the handle in its lowered position with its knife down, as shown in Fig. 2, the action on raising the handle is to move the handle and knife rearwardly by the shape of 80 the slot at a rate just sufficient to cause the corner of the knife to follow a straight vertical line at the center of the cheese instead of a curved one, as would obtain were it moved around a fixed pivot. 85

Mounted in a lug on the under side of the base and in the bearing I is the shaft Q, which is held in place by the set collar J, and mounted on the shaft is the worm-wheel H, having engagement with the gear G. Secured 90 by means of screws or otherwise to the base A is the circular wooden disk S, which is covered with the graduated plate T, preferably a plate of metal, though other material might be used. 95

K represents balls seated in pockets in the arms of the base to lessen the friction between the rotating plate B and the base A.

Mounted on the outer end of the shaft Q is the crank W, and loosely mounted on the 100 shaft between the crank and the plate T is the threaded bushing Z Z, on which are mounted the gage U and the indicator-hand V, and the last two parts are held frictionally in any given adjustment by the nut Z, which 105 screws upon the threaded bushing in the manner shown in Fig. 6. Secured to the gage-bar U is the spring Y, which bears at its free end toward the disk S, and to this free end of the spring the wooden block X or block 110

of other good friction material is fastened and by the action of the spring makes strong friction-contact with the disk. The right edge of the gage U is in a line diametrically 5 of the graduated plate T. It has the notch 2 to receive the lug 3 on the crank W when the crank is in closest relation to said gage, and the indicator-hand V has the notch 4 to allow its edge to pass the said lug just sufficient to 10 contact with the right-hand edge of gage U.

The operation of the device is as follows: To determine the size of, say, a five-cent slice 15 out of a six-dollar cheese, it is ascertained by dividing six hundred cents by five cents that one hundred and twenty five-cents slices should be obtained. Then by multiplying three hundred and sixty degrees, the degrees of a circle, by twenty-four, the number of teeth in the gear-wheel, the number eight thousand 20 six hundred and forty is obtained, which divided by the above number one hundred and twenty gives seventy-two degrees as the arc of the circle measured on plate T that the crank W must travel to move the board C so as to 25 pass the required quantity of cheese under the knife. The gage U, crank W, and hand V are normally together at the top of the graduated plate T, and after the number seventy-two has been obtained by calculation 30 the hand V is moved down that many degrees on the graduated plate and there remains to act as a stop for the crank when the latter is turned, thus measuring the first five-cent portion. If double that amount, as ten-cents' worth, is required, the block X is drawn 35 out of contact with disk S and the gage-bar U moved till its notched end contacts with the lug 3 on crank W. The friction between bar U and hand V causes the latter to move 40 to a new position seventy-two degrees from the place of its first stop, where it again acts as a stop for the handle W to measure the second five-cents' worth of cheese. The above operations are repeated until as many multiples of five-cents' worth as may be required 45 are measured off.

Having thus fully described my invention, what I claim as new, and wish to secure by Letters Patent, is—

- 50 1. In a computing cheese-cutter, a base, a rotary table, brackets mounted on said base having horizontal and cam-shaped slots, a knife having pins entering said slots, a worm-gear secured to said table, a worm-wheel engaging said gear, means for rotating the worm-wheel, and means for measuring and controlling the movement of said wheel, comprising a graduated disk, an index-hand, and a gage-bar to gage the movement of the index-hand.
- 55 2. In a computing cheese-cutter, a base, a pair of brackets supported by said base having horizontal and cam-shaped slots, a knife having pins moving in said slots, a rotary table mounted on said base, ball-bearings be- 60 tween the base and table, a worm-gear of less

diameter than the table, secured to the table, a worm-wheel engaging said gear, a shaft on which the worm-wheel is mounted, means for rotating the worm-wheel shaft, and means for measuring and controlling the movement of said wheel, comprising a graduated disk, an index-hand, and a gage-bar to gage the movement of the index-hand. 70

3. In a computing cheese-cutter, a base, a rotary table mounted on said base; a bracket secured to said base having horizontal and cam-shaped slots, a knife-handle pivotally secured to said bracket by pins entering said slots, and a knife attached to said handle. 75

4. In a computing cheese-cutter, a base, a rotary table mounted on said base upon which the cheese is placed, a pair of brackets secured to said base each having opposite horizontal slots and adjacent cam-shaped slots, a handle having a pin for each set of slots said pins 80 loosely entering said slots, and a knife attached to said handle. 85

5. In a computing cheese-cutter, a rotary table on which the cheese is placed, a lever or handle having oscillatory movement above the 90 table in a plane through the axis of rotation of the latter, a knife secured to said handle and having like oscillatory movement through the whole cutting stroke, and means for moving the knife longitudinally to cause its lower 95 corner to move constantly in a straight line along the axis of the rotary table. 100

6. In a computing cheese-cutter, a rotatable table, brackets having cam-slots, and a knife having pins moving in said slots thereby imparting to the knife a constant compound oscillatory and longitudinal movement radially of the table in a vertical plane whereby one corner of the knife will follow the axis of the table through the thickness of the cheese. 105

7. In a computing cheese-cutter, a rotatable table, brackets having cam-slots, and a knife having pins moving in said slots thereby imparting to the knife a constant compound oscillatory and longitudinal movement in a plane 110 through the axis of the table. 115

8. In a computing cheese-cutter, a base, a rotatable table, a support outside of the table having a horizontal slot and a cam-slot adjacent to the latter, a handle having pins entering both of said slots, and a knife fastened to the handle radially of the table and having a lower corner moving at all positions of its cutting travel in the axis of the table. 120

9. In a computing cheese-cutter, a rotatable table, a pair of brackets supported independently of the table, each having horizontal slots and adjacent cam-slots which pass upwardly and outwardly then upwardly and inwardly and then in curves outwardly or rearwardly 125 over the horizontal grooves, a handle having bifurcated rear ends making a close fit between the pair of brackets, a pair of pins passing through the bifurcated ends of the handle and having ends terminating in said grooves 130

of the brackets, the pin for the cam-grooves having friction-rollers and a knife attached to said handle.

10. In a computing cheese-cutter, a rotatable table, a worm-gear secured to the under side thereof, a worm-wheel engaging the worm-gear, a shaft on which the worm-wheel is mounted, a circular graduated plate at the edge of the table through which said shaft passes, a crank on the end of the shaft, a bushing mounted loosely on the shaft between the plate and crank, a gage-bar on the bushing reaching diametrically of the graduated plate and having a friction-block at one end to engage the rim of the plate and an adjustable index-hand also mounted on the bushing.

11. In a computing cheese-cutter, a rotatable table, a worm-gear secured to the under side of the table, a shaft, a worm-wheel mounted on the shaft and engaging the worm-gear, a graduated circular plate fixed at the edge of the table through which the shaft passes, a crank on the end of the shaft, a gage-bar and an index-hand between the crank and the graduated plate adjustable in angular relation with each other but ordinarily moving together, and means for holding a given position of each.

12. In a computing cheese-cutter, a rotatable table, a worm-gear secured to the under side of the table, a shaft, a worm-wheel mounted on the shaft and engaging the worm-gear, a

circular wooden disk fastened near the edge of the table, a graduated plate outside of said disk, said shaft passing through the plate and disk, a crank on the outer end of the shaft, a threaded bushing loosely mounted on the shaft between the crank and graduated plate, a gage-bar and an index-hand mounted on the bushing, a nut screwing on the bushing to frictionally join the said bar and hand, said bar having an end spring and a friction-block secured to the spring and pressed by it against the disk, said crank having an inside lug and said bar and hand having edge notches to receive the lug.

13. In a computing cheese-cutter, a rotatable table, a pair of brackets supported independently of the table, each having horizontal slots and adjacent cam-slots which pass upwardly and outwardly then upwardly and inwardly and then in curves outwardly or rearwardly over the horizontal grooves, a handle having parts making close fit between the pair of brackets, pins from said handle moving in said grooves of the brackets and a knife fixed to the handle.

In witness whereof I have hereunto set my hand and seal at Indianapolis, Indiana, this 14th day of July, A. D. 1904.
